UNITED STATES PATENT OFFICE.

EVERETT A. PHILLIPS, OF SUMMIT, NEW JERSEY, ASSIGNOR, BY MESNE ASSIGNMENTS, TO THE CREAMERY PACKAGE MFG. COMPANY, OF CHICAGO, ILLINOIS, A CORPORATION OF ILLINOIS.

ICE-CREAM-BRICK CAVE.

Application filed September 23, 1920. Serial No. 412,110.

To all whom it may concern:

Be it known that I, EVERETT A. PHILLIPS, a citizen of the United States, residing at Summit, in the county of Union and State 5 of New Jersey, have invented certain new and useful Improvements in Ice-Cream-Brick Caves, of which the following is a specification.

My present invention relates to ice cream 10 caves or containers particularly adapted for holding ice cream in brick form in such a manner that it may be readily vended from the container a brick at a time with a minimum amount of trouble and particularly with a minimum disturbance of the refrigerant surrounding the container.

With these and other objects in view, my invention consists of the combinations and arrangements herein described and specifically pointed out in the appended claim.

In the drawings, Figure 1 is a sectional elevation of one form of my invention, and Fig. 2 is a perspective view of the container illustrated in Fig. 1.

Like parts have like reference characters in the several views.

In the drawings, 10 is a tub which may be any of the suitable and usual forms for containing the refrigerating material, 30 usually a mixture of cracked ice and salt. 11 is a container, which in the form illustrated, is a can having vertical walls and being of rectangular cross section and of a size sufficient in area so that a plurality of 35 ice cream bricks in the usual cartons 12 may be placed side by side, the container in the form illustrated being large enough to contain two rows of four bricks each on each layer with one layer of bricks on their sides 40 at the bottom of the container.

A cover or lid 13 extends over the vertical sides of the container 11, so that when this cover 13 is removed access may be had to all of the interior of the container 11, so 45 that the container may be readily cleansed and filled with the ice cream bricks. Preferably the top of the cover 13 is flat, for a purpose to be pointed out hereinafter.

In the center of the cover 13 is an opening, circular in form in the illustration, this opening being surrounded by a raised portion 14 of the cover 13. A supplemental cover 15 is adapted to extend over the raised

portion 14 and is provided with a suitable handle 16.

Preferably the opening in the cover 13 is formed centrally of that cover and of a size such that a single brick may conveniently be withdrawn from the container 11 through the opening when the supplemental cover 15 is removed. In order that there shall be as much of the top of the cover 13 left as is possible, I preferably make the central opening in that cover small enough so that two of the bricks cannot be removed at a time.

In use the container 11 is packed with the ice cream bricks, as best shown in Figure 1, and then the cover 13, with the supplemental cover 15, is placed on the container. 70 The loaded container is then packed in the refrigerating material which may be heaped over the top of the container, including the lid 15, so that the entire container is surrounded with the refrigerant.

When it is desired to vend a single brick from the container it is necessary merely to push the refrigerating material away from the relatively small cover 15, leaving the refrigerant extending over the top of the 80 cover 13, as shown in Fig. 1. The raised portion around the central opening prevents the refrigerant from falling into the container when the cover 15 is removed. Then a single brick may be withdrawn and 85 the cover 15 replaced with a minimum disturbance of the refrigerant surrounding the container, and with a minimum possibility of any of the refrigerant falling into the container when the single package is being 90 removed.

By making the cover 13 flat it is possible to maintain some of the refrigerant on top of the lid 13 at all times. By making the opening covered by the supplemental lid 95 15 small in comparison with the total area of the container, I also provide a maximum surface on which the refrigerant can lie above the container, while, at the same time, permitting the bricks to be vended one at a 100 time, as is usually desired. It will also be understood that the raised portion 14 may be of any suitable height above the normal level of the cover 13, so as to permit the desired quantity of refrigerant to lie on 105 the flat portion of the cover 13 without fall-

ing into the container when the cover 15 is removed.

While I have shown my container in its preferred form of a rectangular can, it will be understood that any other desired shape may be used. It will also be understood that the relative dimensions of the container may be varied in accordance with the sizes and shapes of the packages to be held therein and vended therefrom.

I claim:

In combination, a tub adapted to hold a

refrigerant, a container in the tub and having vertical walls, and a main cover extending over the vertical walls, said main cover having an opening of less than half the area of the top of the container, said opening being surrounded by a raised portion and a supplemental cover for said opening, whereby access to the interior of the container may be had through said opening while the remaining portion of the main cover has refrigerant over and around it.

EVERETT A. PHILLIPS.
